UNITED STATES PATENT OFFICE.

WILLIAM HOGENSON, OF CHICAGO, ILLINOIS, ASSIGNOR TO CHICAGO VITREOUS ENAMEL PRODUCT COMPANY, OF CICERO, ILLINOIS, A CORPORATION OF ILLINOIS.

WORKTABLE FOR USE IN COATING ARTICLES.

Application filed September 3, 1922. Serial No. 586,910.

To all whom it may concern:

Be it known that I, WILLIAM HOGENSON, a citizen of the United States, and a resident of Chicago, county of Cook, and State of Illinois, have invented certain new and useful Improvements in Worktables for Use in Coating Articles, of which the following is declared to be a full, clear, and exact description.

10 This invention relates to work table for use in coating articles and its principal object is to provide a traveling work support with means for turning the articles, while they are being sprayed, whereby all of the 15 sides of the articles, except perhaps the bottom, may be sprayed, during the interval that the article is passing the operator's station. Another object is to reduce to a minimum, the time usually required for applying 20 enamel to the wares. Another object is to provide a device upon which two operators may work at one and the same time, whereby all sides of the articles may be treated from the time they are placed on 25 the table until removed therefrom, thus dispensing with the necessity of handling them more than once. Other objects and advantages will appear in the course of the following specification, and with all of said objects and advantages in view, this invention 30 consists in the several novel features herein-after fully set forth and claimed.

The invention is clearly illustrated in the accompanying drawings, in which:

35 Fig. 1 is a plan, partly broken away, of an enamel ware spraying table, embodying a simple form of the present invention and Fig. 2 is a vertical, central section thereof, taken on the line 2-2 of Fig. 1.

40 Referring to said drawings, which illustrate one embodiment of the invention, the reference character 5 designates the base of the device upon which is rotatively mounted a carrier, here shown in the form of a spider like frame 6, which supports turn tables 7, that are rotatively mounted on the carrier 6, and are driven to rotate upon their own axes at certain stations during the rotation of the carrier 6. The base 5 may be 45 of any suitable form and, as shown, comprises a central housing 8, in which is mounted a vertical shaft 9 to which is secured the carrier 6. On the top of the housing 8 is supported a ball race 10, above 50 which and spaced therefrom, is a second ball

race 11, between which is a circular plate 12 formed on a hub portion 13 of the carrier 6. Antifriction balls or other antifriction members 14 are interposed between the ball races 10, 11 and plate 12, to provide an anti-friction bearing for the carrier 6. The housing 8 may have an annular wall 15, above its top portion 16, which extends above and protects the antifriction bearing members, and a ring 17, may be secured to 60 said wall 15 to cover the ball races, and set screws 18 may be threaded in said ring to bear against the upper ball race thereby holding the same in place. At the bottom of the housing is secured a bracket arm 19 in which the lower end of the shaft 9 is journaled. The rotating carrier 6 may be 65 rotated by any suitable means and it is here shown as being power driven, from an electric motor 20. A speed-reducing gearing 70 element 21 is interposed between the motor and rotating carrier 6, and the drive connections between said speed reducing gearing and rotating carrier, may comprise a beveled pinion 22 on the shaft of said gearing, 75 and a beveled gear wheel 23 mounted on the shaft 9 of the rotating carrier 6.

Bolted or otherwise secured to the hub 13 of the carrier 6, are arms 24 that radiate from the hub 13, and support the turn tables 7. Said arms are preferably T shaped in cross section, and upon the webs 24^a of said arms, are removably supported drip pans 25 which fill in practically all of the spaces between the arms 24, and catch any 80 drippings from the articles or any enamel or other paint or coating material that is sprayed upon the articles carried by the turn tables 7. The marginal edges 26 of the drip pans are bent up, as shown. The 85 drip pans 25 may be readily removed from the rotating carrier 6 for the purpose of cleaning them. They are formed with openings 25^a around which are bent up edge portions 26^a. The openings receive certain 90 shafts, as will be hereinafter set forth.

Secured to and connecting the outer ends of the arms 24 are struts or bracket arms 27 in which are journaled upright shafts 28 located midway between the arms and projecting through the holes 25 in the pans, and on the upper ends of said shafts 28 are removably secured the turn tables 7, as for instance the upper ends of the shafts 28 may be flattened, and the turn tables may 100 105 110

have hubs 29 secured on their lower faces, which are formed with correspondingly flattened sockets for the reception of the flattened upper ends of the shafts 28. The 5 lower ends of the shafts 28 are journaled in lugs 27^a formed on said struts or bracket arms 27. Upon the lower ends of the shafts 28 are secured pinions 30 that are arranged to come into mesh with one or more gear 10 segments 31, 31^a, located at a certain place or places about the base, whereby, as the turn tables pass said gear segments, they are thereby rotated upon their own axes to thereby present the various sides of the articles 15 carried thereby, to the operator. In the drawings two gear segments 31, 31^a are shown, whereby the turn tables may be caused to rotate on their own axes at two places about the base, but a lesser or greater 20 number of gear segments may be employed when necessary. The gear segments are secured to upstanding bracket members 32 bolted or otherwise secured to frame members 33 of the base 5.

25 Located above the places where the turn tables rotate upon their axes, are spraying cabinets 34, 34^a through which the articles are moved for treatment. The cabinets comprise box like structures closed at the top 35, sides 36, and back 37, 37^a, their fronts and bottoms being open. Their rear sides 37^a slope downwardly and upwardly as shown, and leading from their rear sloping sides 37^a are outlet conduits 38, 38^a, which join with 30 an outlet conduit 50, which leads to an exhaust fan (not shown). Dampers 39, 39^a are placed in the outlet conduits, 38, 38^a whereby either conduit may be closed to its cabinet, so that the air current may be moved 35 through the one employed. A receptacle 40 is placed in communication with the conduits 38, 38^a in such position as to catch any liquids that may fall through the conduit 50. The cabinets are supported by any suitable 40 means, here shown as comprising upright posts 41 and horizontal members 42, secured thereto to which the cabinets are attached. Openings 43 in the side walls of the cabinets, partly closed by doors 43^a, permit the articles 45 to pass through the cabinets from side to side.

50 In the operation of the device, and assuming that all sides of the articles are to be enameled or otherwise coated or sprayed, the unfinished articles are placed on the turn 55 tables at some point between the two cabinets or operators' stations. Power being applied to the rotating carrier, the latter is rotated and as each pinion 30 comes into mesh with the gear segment under one cabinet, the pinion is rotated and therewith the turn table 60 mounted thereon, and the articles carried by the turn table. The table is given at least one complete revolution upon its axis, as it passes through the cabinet, thereby display-

ing the top and all sides of the articles from all angles, to the attendant or spraying operator who is stationed in front of the cabinet. He sprays the articles as they pass through the cabinet thereby covering all 70 sides, which are exposed or presented to him. When the pinion 30 runs off the gear segment, the turn table stops rotating and an attendant may invert the articles carried thereby, so that the side which was undermost 75 may be sprayed when the articles reach the other cabinet. After they leave the cabinets they are removed and replaced by unfinished ones, and in this manner the operation may be made continuous, and very rapid. 80

The suction created in the cabinets carries off any of the spray which does not strike and adhere to the articles or walls of the cabinet.

85 Whenever it becomes necessary to change colors, the machine is stopped, the turn tables removed from their shafts and cleaned, and the drip pans removed from the machine and the drippings poured out and the pans thoroughly cleaned and replaced after which 90 the turn tables are replaced on their shafts.

The device has been particularly designed for use in spraying enamel upon wares of various descriptions, but it may be used for spraying or applying other coatings or 95 surfacing material to articles of various kinds.

More or less variation of the exact details of construction is possible without departing from the spirit of this invention; I desire, therefore, not to limit myself to the 100 exact form of the construction shown and described, but intend, in the following claims, to point out all of the invention disclosed herein.

I claim as new and desire to secure by Letters Patent:

1. A spraying table, comprising in combination, a base, a bracket secured thereto, a stationary gear segment secured to and supported by said bracket, an upright shaft 110 journaled in said base, power mechanism for said shaft, horizontal supporting arms secured to and radiating from said shaft, struts connecting the free ends of said arms, upright circumferentially arranged pinion 115 shafts journaled in bearings on said struts and projecting above and below said struts, pinions secured on the lower end of pinion shafts and arranged to come into said mesh with said gear segment, horizontal turn 120 tables located above said struts and removably secured on said pinion shafts, and circumferentially arranged removable drip pans below said turn tables set contiguous with each other.

125 2. A spraying table comprising a rotatory frame, drip pans removably resting on said frame, turn tables removably supported above said drip pans, and means for intermittently rotating said turn tables on their 130

own axes, including pinion shafts, one for each turn table, each shaft extending above and below the bottom of an associated drip pan.

5. 3. A spraying table comprising a rotatory frame having a central hub portion and arms radiating therefrom, drip pans extending between and removably secured upon said arms, each drip pan having a flanged opening in its bottom, removable turn tables located above said drip pans and means below said drip pans for intermittently rotating said turn table upon their own axes, including shafts, one for each turn table extending 10 through the opening in an associated drip pan.

4. A spraying table comprising a rotatory frame having a central hub, arms radiating therefrom and struts connecting the ends of said arms, drip pans removably secured upon 20 and extending between said arms, each drip pan having a flanged opening in its bottom, removable turn tables located above said drip pans, driving mechanism for intermittently rotating said turn tables, including pinions 25 and shafts, said shafts extending through said flanged openings in the bottom of the drip pans and being connected to said turn tables, and stationary gear segments with which said pinions are arranged to mesh.

WILLIAM HOGENSON.
